US00D803981S

(12) **United States Design Patent** (10) **Patent No.:** **US D803,981 S**
(45) **Date of Patent:** **** Nov. 28, 2017**

(54) **HANDHELD SPRAY NOZZLE**

(71) Applicant: **WATER PIK, INC.**, Fort Collins, CO (US)

(72) Inventor: **Jeffrey Thurgood**, Fort Collins, CO (US)

(73) Assignee: **Water Pik, Inc.**, Fort Collins, CO (US)

(**) Term: **15 Years**

(21) Appl. No.: **29/553,444**

(22) Filed: **Feb. 1, 2016**

(51) LOC (10) Cl. **23-01**

(52) U.S. Cl.

USPC **D23/223**

(57) **CLAIM**

The ornamental design for a handheld spray nozzle, as shown and described.

DESCRIPTION

FIG. 1 is a front isometric view of an embodiment of a handheld spray nozzle.

FIG. 2 is a front elevation view of the handheld spray nozzle of FIG. 1.

FIG. 3 is a rear elevation view of the handheld spray nozzle of FIG. 1.

FIG. 4 is a left side elevation view of the handheld spray nozzle of FIG. 1.

FIG. 5 is a right side elevation view of the handheld spray nozzle of FIG. 1.

FIG. 6 is a top plan view of the handheld spray nozzle of FIG. 1; and,

FIG. 7 is a bottom plan view of the handheld spray nozzle FIG. 1.

The broken line showing of portions of the spray nozzle form no part of the claimed design.

1 Claim, 4 Drawing Sheets
